United States Patent Office

Des. 220,419
Patented Apr. 6, 1971

220,419

SOLID SURFACE FLOOR COVERING OR SIMILAR ARTICLE

Robert R. Toth, Toms River, and Harry A. Shortway,
Glen Rock, N.J., assignors to Congoleum Industries,
Inc., Kearny, N.J.

Filed May 5, 1969, Ser. No. 18,424

Term of patent 14 years

Int. Cl. D6—04

U.S. CL. D92—4

FIG. 1.

12

FIG. 2.

FIG. 1 is a plan view of a solid surface floor covering embodying our new design showing a regular repeating unit;

FIG. 2 is a sectional view taken along lines 2—2 of FIG. 1;

FIG. 3 is a view of a portion of FIG. 1; and
FIG. 4 is a sectional view taken along lines 4—4 of FIG. 3.

We claim:

The ornamental design for a solid surface floor covering or similar article, substantially as shown and described.
